CHECK INDORSING MACHINE

Filed July 13, 1928

UNITED STATES PATENT OFFICE

LAWRENCE J. ZAHM, OF LONG ISLAND CITY, NEW YORK, ASSIGNOR TO INTERNATIONAL POSTAL SUPPLY COMPANY, OF BROOKLYN, NEW YORK

CHECK-INDORSING MACHINE

Application filed July 13, 1928. Serial No. 292,386.

This invention relates to a check indorsing machine used by banks, for the purpose of stamping certain indicia on said checks as they pass through the bank.

5 It is one of the objects of my invention to provide various improvements in the detailed construction and method of operation of this type of machine. My invention is directed to improved means in the method of feeding the 10 checks through the machine, and in stacking them in the check stacking compartment; also in an improved form of die roller and an ink feeding mechanism as well as other general improvements, which will be disclosed in the 15 specification, and set forth in the appended claims.

In the drawing Figure 1 is a plan of my improved check indorsing machine with the cover thrown back exposing the interior 20 parts, the die plate being removed from the die structure.

Figure 2 is a side view of Figure 1, some of the parts being shown in a secondary position by dotted lines.

25 Figure 3 is an end view of the machine.

Figure 4 is a fragmentary view showing a detail of means for moving the carrier frame used in the construction of the machine.

Figure 5 is a detail view showing the 30 mounting for the carrier frame.

Figure 6 is a sectional view through my improved form of drive roller.

Referring now to the details wherein like 35 numbers refer to corresponding parts in the various views:

1 is a framework of my check indorsing machine, within which is mounted a small electric motor 2 for the purpose of driving the mechanism. The motor 2 has a pinion 3 meshing with a gear 4, with which is associated a gear 5 that meshes with a gear 6, attached to a drive roller 7. The drive roller 7 shown in section in Figure 6, comprises a body portion acting as an impression roller having over the greater part of its length, a surface 8 of a suitable grade of rubber or the equivalent thereof. The end of the drive roller adjacent the gear 6, is preferably made up of rubber discs 9 separated by disc 10 of some suitable fibrous material, such as

canvas, although it is to be understood that this portion may be made up of canvas material which has been thoroughly impregnated, with a suitable rubber or equivalent compound. This portion of the drive roller just referred to is made to engage with the clutch roller, comprising part of the die structure which will be later described. The drive roller spindle 11 is carried on anti-friction bearings 12 and 13, the inner portions of which support a shaft which is not shown in Figure 6. The drive roller is provided with two grooves 14 and 15, in which are positioned a pair of guide fingers which will be later referred to. Over the top part of the frame 1 is mounted a cover plate 16, one end of which is bent downward over the drive roller 7, and this plate 16 is used for feeding the checks down onto the drive roller. On the opposite end of the machine from the position of the electric motor 2, a carrier frame 17 is mounted. The carrier frame has two side arms 18 and 19, and these are mounted on a rod 20 which has holes 21, in each end, that are positioned in an eccentric manner, as shown in Figure 5, and positioned in these holes are shoulder pivot studs 22 and 23. On the free ends of the carrier frame which includes the arms 18 and 19 as described is mounted a die structure 24. This die structure is generally of a construction similar to that shown in Jahn Patent 1,623,478, issued April 5, 1927, in which several groups of a series of type blocks 25 are adjustably mounted so that any die block of a series may be brought into printing 85 position as determined by a die plate not shown in Figure 1, on which plate, certain fixed indicia is usually cut or engraved.

My improvement with respect to this die structure per se, is the subject matter of a 90 separate application Serial No. 292,387, filed July 13, 1928, and will not therefore be further described herein. In order to move the die structure away from the drive roller 7, the carrier frame is provided with a pair of arms 36 and 37 which meet at a common point and which preferably are integral with the carrier frame, and at this common point a stud 38 is provided attached to the rear wall 39 of the frame. The stud 38 passes through 95

the junction point of the arms 36 and 37, and associated with it is an adjusting nut 40, threaded as shown in Figure 4. The stud 38 is provided with a notch 41 which is adapted to engage the head of the nut 40 as shown in Figure 4, and a spring 42 is used to return the carrier frame to its normal position on releasing the nut 40 from the notch 41. When pressure is applied to the adjusting nut 40, toward the frame, this raises the inner end of the carrier frame, so that the arms 18 and 19 will take the position indicated by the dotted line 43 (see Fig. 2), thereby lifting the die structure from engagement with the drive roller, and the die plate can be then removed for the purpose of adjusting the die block to get suitable indicia for the check stamping operation.

On one end of the shaft 44, of the die structure is slidably mounted by a key not shown, a clutch element 46. The clutch element 46 engages within the clutch housing a clutch plate of any suitable material such as cork or composition thereof, which in turn engages a clutch roller 48 carried on a suitable bearing. The clutching effort is regulated by a spring 49, and adjusting nuts 50, and the surface of the clutch roller 48 is adapted to engage the friction surface formed by the parts 9 and 10 of the drive roller 7, the rubber portion of this part of the drive roller being adapted to provide friction and the fabric portion to resist wear, and I have found that the combination of two such materials gives the best results in a machine of this character.

On the opposite end of the die structure from the drive roller 48 is carried a trip mechanism 51 generally of the same type as disclosed in Jahn Patent 856,845, issued June 11, 1907. The lever 52 of the trip mechanism is adapted to be engaged by the checks as they pass by the drive roller 7 and the die structure 24, thereby allowing the clutch structure 24 through the medium of the clutch just described to turn the die structure and plate so the desired inscription may be stamped on the check as it passes between the drive roller and the die.

In order to properly actuate the trip mechanism and to pass the checks between the drive roller and the die, a pair of trip guide rollers 25 and 26 are provided. The trip tongue is engaged by that part of the check spaced between these guide rollers; also a plurality of fingers 53 are provided. At least one pair of these fingers have their ends extending downward into the check receiving compartment 54. As shown in Figure 2, one pair of the fingers 53 are positioned within the slots 14 and 15 in the drive roller, as previously referred to and as so positioned, are slightly below the periphery of the drive roller, as will be seen from Figure 2. A guide plate 55 may be attached to the bottom of the

carrier frame to assist in guiding the checks to the compartment 54. As shown in Figure 2 this comprises a member 56, which has serrations 57. As the checks pass between the drive roller and the die, the incoming edge thereof is thrown forward into engagement with one of the serrations 57, thereby slightly retarding, for a brief interval, this edge of the check, allowing the leaving edge to drop downward toward the bottom of the compartment, as indicated by the dotted lines 58. I have found that without this special means that the checks are quite apt to strike against the outer wall of the compartment and stick there in a sidewise position, but the means just described absolutely eliminates this difficulty.

As a further aid in insuring that the checks are properly stacked in the compartment 54, I have provided the eccentric mounting of the carrier frame on the shaft 20, as previously described, and by means of pins inserted in the holes 59, the rod 20 can be turned and on account of the eccentric position of the fixed pin 21, the carrier frame is moved so that the die structure is moved a short distance, arcuately around the drive roller 7, thereby changing the angle at which the checks enter the compartment 54.

The combination of these two special arrangements gives a highly satisfactory result. Supported on the carrier frame is an auxiliary frame 60, having side plates 61 and 62. This auxiliary frame carries a felt roller 63, an ink roller 64, and a wiper roller 65. The felt or ink absorbent roller 63 has its bearing ends carried by a slot 80 in each of the side plates 61 and 62, and is resiliently held in position by the springs 66 and 67, in engagement with the ink roller 64, which in turn is positioned so as to carry ink from the bottom of the auxiliary frame to the ink absorbent roller 63. The amount of ink which the ink roller 64 will carry to the roller 63 is regulated by the wiper roller 65, which latter roller has its ends positioned in grooves 68, in the plates 61 and 62. The roller 65 is held in position in the groove 68 by means of a pair of roller bushings each having flanges 69 and 70 between which flanges, rests a spring 71, the tension of which can be adjusted by a screw 72, so as to give the desired pressure of the wiper roller 65 on the ink roller 64. A spring pawl 73 and a ratchet 74 on the ink roller 64 is provided to prevent the ink roller from being turned in reverse direction, which would cause an unregulated amount of ink to be carried up onto the absorbent roller 63. The auxiliary frame is adjustable with respect to the die so as to get the proper pressure of the roller 63 on the die, by means of adjusting screws 75, and lock nuts 76, cooperating with their studs and slots 77. Adjusting studs 75 are carried on a back plate 78.

As will be seen from Figure 2, the cover

79, only the lower part of which is shown, is hinged to the frame 1, so as to be swung over the die structure and its associated parts, thereby keeping the dust from gathering on the mechanism supported by the carrier frame 5 and the auxiliary structure thereon. It is evident that in a machine of this character, many of the details entering into the construction may be varied considerably, and I 10 therefore, do not wish to be unduly limited to the precise construction shown in the drawing.

Having thus described my invention, what I claim is:

15 1. For a check indorsing machine including the following instrumentalities; a drive roller and means for operating the same, a clutch roller having a part normally in engagement with the drive roller, a die structure, a clutch mechanism between the clutch roller and the die structure, a trip mechanism for controlling the movement of the die structure, means for guiding checks between the drive roller and the die and check stacking 20 means below the die structure comprising; a compartment having associated with its vertical wall farthest from the die, a serrated portion for catching the edge of the check, thereby causing the check edge last to leave the die, to drop toward the bottom of the compartment. 25

30 2. For a check indorsing machine including the following instrumentalities; a drive roller and means for operating the same, a clutch roller having a part normally in engagement with the drive roller, a die structure, a clutch mechanism between the clutch roller and the die structure, a trip mechanism for controlling the movement of the die structure, a stacking compartment below the die structure; a plurality of fingers extending over but slightly below the periphery of the drive roller for guiding the checks by the die structure, at least two of said fingers extending into the stacking compartment, the vertical wall of the compartment farthest from the die having serrations associated therewith for catching the edge of the check thereby causing the check edge, last to leave the die, to drop toward the bottom of the compartment. 45

50 3. For a check indorsing machine including the following instrumentalities; a drive roller and means for operating the same, a clutch roller having a part normally in engagement with the drive roller, a die structure, a clutch mechanism between the clutch roller and the die structure, a trip mechanism for controlling the movement of the die structure, a stacking compartment below the die structure; means for guiding the checks by the die into said compartment, and means associated with the vertical wall of the compartment farthest from the die for catching the edge of the check, thereby causing the 55

check edge, last to leave the die, to drop toward the bottom of the compartment.

4. For a check indorsing machine including the following instrumentalities; a drive roller and means for operating the same, a clutch roller having a part normally in engagement with the drive roller, a die structure, a clutch mechanism between the clutch roller and the die structure, a trip mechanism for controlling the movement of the die structure, a stacking compartment below the die structure; means for guiding the checks by the die into said compartment, and means associated with the vertical wall of the compartment farthest from the die for catching the edge of the check, thereby causing the check edge, last to leave the die, to drop toward the bottom of the compartment, and means for shifting the relative position of the drive roller and the die structure whereby the angle at which the checks engage said edge catching means, is altered to secure the best stacking effect. 70

5. For a check indorsing machine including the following instrumentalities; a drive roller and means for operating the same, a clutch roller having a part normally in engagement with the drive roller, a die structure, a clutch mechanism between the clutch roller and the die structure, a trip mechanism for controlling the movement of the die structure, a stacking compartment below the die structure; means for guiding the checks by the die into said compartment, and quickly adjustable means for shifting the relative position of the die structure and drive roller, whereby the angle at which the checks enter said compartment, is altered to aid in securing the best stacking effect. 75

6. For a check indorsing machine including the following instrumentalities; a drive roller and means for operating the same, a clutch roller having a part normally in engagement with the drive roller, a die structure, a clutch mechanism between the clutch roller and the die structure, a trip mechanism for controlling the movement of the die structure, a stacking compartment below the die structure; means for guiding the checks by the die into said compartment, a carrier frame for supporting the die structure, an eccentric rod carrying one end of the carrier frame, means for turning said eccentric rod so as to arcuately move the die about the drive roll, thereby altering the angle at which the checks enter said compartment and means within the compartment for engaging the entering edge of the check to temporarily hold it until the following edge drops toward the bottom of the compartment. 80

7. For a check indorsing machine including the following instrumentalities; a drive roller and means for operating the same, a clutch roller having a part normally in engagement with the drive roller, a die struc- 85

ture, a clutch mechanism between the clutch roller and the die structure, a trip mechanism for controlling the movement of the die structure, a stacking compartment below the die structure; a guide plate just below the die and a plurality of fingers extending over but slightly below the periphery of the drive roller for guiding the checks by the die into said compartment, one wall of the compartment 10 facing the incoming edge of a check having means associated therewith for detaining said incoming check edge if the same reaches said wall.

8. In a check indorsing machine, a stationary framework having a check receiving compartment at one end and a compartment at the other end for power driving mechanism including a driving roller, a feed table closing the top of the power compartment and extending downward to the driving roller, a carrier frame pivoted so as to extend over the check receiving compartment, a printing die structure and trip controlling mechanism mounted on the free end of said 25 carrier frame so as to operatively engage said drive roller, a roller of absorbent material, an ink roller and a wiper roller also mounted on the carrier frame, and adjustable as a unit with respect to the die structure, a cover fitting over the carrier frame and the parts carried thereby, said pivotal support for the carrier frame including means whereby the carrier frame may be shifted so the die structure moves in an arc with respect to the drive 30 roller thereby shifting the angle at which the checks enter their compartment.

9. In a check indorsing machine having as a part of its mechanism a drive roller and a printing die structure, a clutch roller mounted on the die shaft and connected to the die by adjustable clutch members, said drive roller having its driving surface which engages the clutch roller made up of alternate layers of rubber and fabric and further having 45 grooves in its periphery for check guide fingers as and for the purposes described.

10. In a check indorsing machine having as a part of its mechanism, a drive roller and a printing die structure, a clutch roller mounted on the die shaft and connected to the die by adjustable clutch members, said drive roller having its driving surface which engages the clutch roller, made up of at least two friction materials, one of which has greater 55 wearing qualities than the other, while said other one possesses greater adhesive qualities than the first mentioned material.

In testimony whereof, I affix my signature.
LAWRENCE J. ZAHN.
